BAR STOOL

Jerry Johnson, Hiway 94-Rancho Cuello,
Potrero, Calif. 92063

Filed June 26, 1972, Ser. No. 266,314

Term of patent 14 years

Int. Cl. D6—01

U.S. Cl. D6—35

FIG. 1

FIG. 2

FIG. 3

FIG. 4

FIG. 5

FIG. 1 is a perspective view of a bar stool showing my new design;

FIG. 2 is a side elevational view thereof showing the side not visible in FIG. 1;

FIG. 3 is a rear elevational view thereof;

FIG. 4 is a top plan view thereof, and

FIG. 5 is a bottom plan view thereof.

I claim:

The ornamental design for a bar stool, substantially as shown.
